RAILWAY CAR CONSTRUCTION

Charles D. Bonsall, Pittsburgh, Pa., assignor, by
mesne assignments, to Standard Railway De-
vices Company, a corporation of Delaware

Application April 20, 1939, Serial No. 269,005

9 Claims. (Cl. 98—6)

The invention relates to ventilated house cars and particularly to the conversion of refrigerator cars to cars adapted to be operated under ventilation.

A common type of refrigerator car which has been in general use for a period of many years has ice bunkers disposed adjacent opposite end walls of the car with hatches thereabove in the roof for loading refrigerant. The central portion of the car is the lading compartment; bulkheads are provided adjacent each ice bunker to define the ends of the lading compartment. The bulkheads have considerable strength to resist the thrusts of the lading caused by service movements of the car. The lading is commonly supported within the lading compartment by floor racks which provide a space between the lading and the floor of the car. The bulkheads are spaced from the floor and from the roof so that air, upon being cooled by the refrigerant in the bunker circulates under the bulkheads to the space below the lading. The air then circulates upwardly through the floor rack, which is foraminous for the purpose, through the lading compartment and over the bulkheads to the ice bunkers.

In recent years, more modern types of refrigerator cars have seen considerable service. There are mechanical refrigerator cars, dry ice cars, side bunker cars and particularly overhead bunker cars. The last mentioned is becoming increasingly popular because it is more efficient due to the height of the refrigerant above the lading, making possible the maintaining of lower and more uniform temperatures. In addition, more space is available for the lading on account of the absence of ice bunkers at the ends of the cars.

The advent of the new types of refrigerator cars has presented the problem of disposing of the old cars. It is not economically sound to operate an old type of car when a new and more efficient type is available. Neither is it sound to scrap cars which are in good mechanical condition and have years of service remaining. It is an object of this invention to convert refrigerator cars to ventilated cars. Many fresh fruits and vegetables give off heat during storage or transportation. This heat results from chemical changes occurring within the fruit or vegetable, such as ripening. While many such products may be safely transported at any temperature within a relatively wide range it is important that fresh air be supplied continuously to carry away the heat which is constantly emitted. To

allow the heat to remain within the lading compartment is to increase the temperature excessively with a consequent acceleration of ripening and possible spoilage.

It is an object of this invention to convert a refrigerator car to a ventilated car by providing means for the air to enter through the hatches at one end of the car, permeate through the lading within the car and flow out of the car through hatches positioned at the opposite end of the car.

Another object of the invention is to provide means to prevent water from entering the hatches and reaching the lading. Many types of lading are damaged by moisture and since cars must be ventilated during rainy weather, means must be provided to trap the moisture which accompanies the ventilating air.

A further object is to adapt the car so that air may enter at either end and flow out at the opposite end, thereby permitting the car to be operated in either direction.

Other objects and advantages of my invention will be apparent from the following detailed description taken in reference to the accompanying drawings.

In the drawings:

Fig. 1 is a longitudinal section of a car embodying my invention.

Fig. 2 is a transverse section on line 2—2 of Fig. 1.

Fig. 3 is a broken away perspective view of a car showing direction of air flow.

Fig. 4 is a longitudinal section of a refrigerator car from which the car shown in Figs. 1 to 3 was converted.

Fig. 4 shows an end bunker refrigerator car comprising roof 2, end walls 3, floor 4, ice bunkers 5, bulkheads 6, hatches 7, lading compartment 8, floor rack 9 and space 10 between the rack and floor. Like numerals indicate like parts in all figures.

The conversion of the refrigerator car of Fig. 4 to a ventilating car comprises removal of the bunkers 5 and bulkheads 6 and the addition of parts which will be hereinafter described. Insulating hatch covers 20 are commonly provided to prevent ingress of warm air to refrigerator cars. The covers ordinarily have no fixed relation to the hatch frames 21 but are attached thereto by means of a chain to prevent loss; in more modern cars, the covers are often hinged as shown in Fig. 1. The conversion of some types of cars requires no changes in hatch cover arrangement to conform to that shown in Fig. 1;

in other types of cars, the hinges 24 and supporting pieces 25 must be added. The supporting pieces 25 are preferably adjustable so that the covers 20 may be opened varying distances. Additional sections of floor racks 27 should also be added to the portion of the car originally occupied by the ice bunkers 5.

The ventilating means comprises means to direct air from outside through the hatches at one end of the car to the space under the floor rack and means to allow the air to escape through the hatches at the other end of the car. A partition 35 is spaced from each end wall 3 to form flues 36 communicating at the lower ends thereof with the space 10 under the floor rack 9. The upper end of each partition 35 is spaced from the roof 2 to form the openings 38. A pan 40 is positioned below each hatch 7; said pan rests at one end thereof upon the upper edge of the partition 35 and is secured at the other end to the side 41 of the hatch frame 42 most remote from the partition 35. Each pan has a wall 45 upstanding therefrom at the edge thereof adjacent the center of the car and a flange 46 at the edge thereof adjacent the side wall of the car. The portion of the car ceiling between the hatches 7 at each end of the car is preferably removed and replaced by a member 48 having its body portion disposed an appreciable distance above the lowermost edge of the hatchframe side 49 adjacent thereto. The flange 46 is preferably secured to the car roof adjacent the hatch 7 and the wall 45 is spaced from the member 48 to provide the opening 51. The walls 45 are spaced apart to provide the duct 52 and each is flared inwardly 54 to prevent moisture from splashing into the duct 52. A baffle plate 55 is provided to prevent communication between the lading compartment 8 and flue 36 between the pans 40 and additional baffle plates 56 are provided for the same purpose between the pans 40 and the side walls 57 of the car.

In Fig. 1, the direction of motion of the car is such that the end 65 is the head or leading end. Air is trapped by the cover 60 and forced to flow downwardly through the flue 68 as shown by the arrows in Fig. 1. It flows into the space 10 and gradually escapes through the floor rack 9 to the lading compartment 8. Some of the air trapped by the cover 60 may flow downwardly through the duct 52 into the upper part of the lading compartment 8 in contact with the lading stored therein. The outflowing air flows upwardly through the duct 52, openings 51 and finally out through the hatches 7. Moisture flowing through the hatches is conducted to the floor of the car by the flues 36 to the floor 4 of the car from where it is drained off through the water sealed drains 72.

It is to be understood that both ends of the car are substantially similar so that the ventilating system operates in a substantially similar manner regardless of direction of motion of the car, air entering through the hatches at the leading end of the car. In the perspective of Fig. 3, air is shown entering and leaving the car through the same hatch. It is not intended that such flow should occur simultaneously but the perspective drawing is included to show the path followed by air entering or leaving.

The accompanying drawings illustrate the preferred form of the invention, though it is to be understood that the invention is not limited to the exact details of construction shown and described, as it is obvious that various modifications

thereof, within the scope of the claims, will occur to persons skilled in the art.

I claim:

1. In a refrigerator having a hatch in the roof adjacent each end of the car, a foraminous rack for supporting a lading on the floor of the car and providing a space therebetween, the combination of a flue associated with each end wall of the car communicating with said space, a pan substantially below each of said hatches arranged to direct air flowing therethrough to the adjacent flue, outlets for the escape of air from the lading compartment of the car through said hatches, and means to trap moisture entering said hatches.
2. In a refrigerator having a hatch in the roof adjacent each end of the car, a foraminous rack for supporting a lading on the floor of the car and providing a space therebetween, and a hatch frame surrounding each of said hatches, the combination of a partition spaced from each end wall to form flues communicating with said space, the tops of said partitions being spaced below said roof, a pan substantially below each of said hatches extending between the upper part of the adjacent partition and the hatch frame side remote therefrom, said pan having an edge underlying said roof, and a wall upstanding from said edge and spaced from said roof to form an opening communicating with the lading compartment of the car.
3. In a refrigerator having a hatch in the roof adjacent each end of the car, a foraminous rack for supporting a lading on the floor of the car and providing a space therebetween, and a hatch frame surrounding each of said hatches, the combination of a partition spaced from each end wall to form flues communicating with said space, the tops of said partitions being spaced below said roof, a pan substantially below each of said hatches sloping downwardly toward the adjacent flue and extending between the upper part of the adjacent partition and the hatch frame side remote therefrom, outlets for the escape of air from the lading compartment of the car through said hatches, and means to trap moisture entering said hatches.
4. In a refrigerator having a hatch in the roof adjacent each end of the car, a foraminous rack for supporting a lading on the floor of the car and providing a space therebetween and a hatch frame surrounding each of said hatches, the combination of a partition spaced from each end wall to form flues communicating with said space, the tops of said partitions being spaced below said roof, a pan substantially below each of said hatches extending between the upper part of the adjacent partition and the hatch frame side remote therefrom, said pan having an edge underlying said roof and a wall upstanding from said edge and spaced from said roof to form an opening communicating with the lading compartment of the car, the upper edge of said wall being flared toward said pan to prevent moisture from splashing through said opening.
5. In a refrigerator having a hatch in the roof adjacent each end of the car, a foraminous rack for supporting a lading on the floor of the car and providing a space therebetween, and a hatch frame surrounding each of said hatches, the combination of a partition spaced from each end wall to form flues communicating with said space, the tops of said partitions being spaced below said roof, a pan substantially below each of said hatches extending between the upper

part of the adjacent partition and the hatch frame side remote therefrom, said pan having an edge underlying said roof and a wall upstanding from said edge and spaced from said roof to form an opening communicating with the lading compartment of the car, the portion of the roof above said wall being at a higher elevation than the lower edge of the hatch frame side adjacent thereto.

6. In a refrigerator car having a pair of spaced apart hatches in the roof adjacent one of the walls of the car, a rack arranged to support a lading upon the floor of the car and provide a space therebetween, and hatch frames surrounding said hatches, the combination of a partition spaced from said wall to form a flue communicating with said space, the top of said partition being spaced from said roof, spaced apart pans substantially below said hatches extending between the upper part of said partition and the hatch frame side remote therefrom thereby forming a path for air from said hatches to said flue, the adjacent edges of said pans underlying the portion of the roof between said hatches and walls upstanding from said edges to form a duct therebetween, said walls being spaced from said portion of the roof to form openings, thereby providing a path for air from the lading compartment through said duct and said openings to said hatches.

7. In a refrigerator having a hatch in the roof adjacent each end of the car and a foraminous rack for supporting a lading on the floor of the car and providing a space therebetween, the combination of a flue associated with each end wall of the car communicating with said space, a pan substantially below each of said hatches

arranged to direct air flowing therethrough to the adjacent flue and outlets for the escape of air from the lading compartment of the car through said hatches.

- 5 8. In a refrigerator having a hatch in the roof adjacent each end of the car, a foraminous rack for supporting a lading on the floor of the car and providing a space therebetween, and a hatch frame surrounding each of said hatches, the combination of a partition spaced from each end wall to form flues communicating with said space, the tops of said partitions being spaced below said roof, a pan substantially below each of said hatches sloping downwardly toward the adjacent flue and extending between the upper part of the adjacent partition and the hatch frame side remote therefrom, and outlets for the escape of air from the lading compartment of the car through said hatches.
- 10 9. In a refrigerator car having a pair of spaced apart hatches in the roof adjacent one of the end walls of the car and a rack arranged to support a lading upon the floor of the car and provide a space between the lading and the floor, the combination of a flue associated with said wall and communicating at its lower end with said space and means associated with each of said hatches to direct air flowing therethrough into the upper part of said flue, said means having side walls adjacent the center of the car extending upwardly and spaced apart to form a vertically extending duct below the portion of the roof between said hatches arranged to provide air communication between said hatches and the upper part of the lading compartment of the car.
- 15 20 25 30 35
